HEAT INSULATED BOTTLE CONTAINER

Edgar Alvin Wickstrom, Marquette, Mich.

Application October 19, 1939, Serial No. 300,269

2 Claims. (Cl. 229—4.5)

This invention relates to a container and it aims to provide such an article as utilizes the insulating properties of dead air space especially in corrugated board, the container being especially adapted for the reception of an infant's feeding bottle when the mother is visiting or motoring or at night and is also useful for packing hot and cold foods for picnics, outings and the like.

Various other uses, advantages and objects will become apparent from a consideration of the description following taken in connection with accompanying drawing illustrating an operative embodiment.

In said drawing—

Figure 1 is a view of the container in central vertical section;

Figure 2 is a cross sectional view taken on the line 2—2 of Figure 1;

Figure 3 is an enlarged longitudinal sectional view of an upper portion of the container and closure, better disclosing details, and

Figure 4 is an enlarged longitudinal sectional view of a lower portion of the container and bottom, to better disclose details.

In carrying out the invention, the container has a generally cylindrical body as at 10. This body consists of a number of layers or sheets, for instance three, of corrugated pasteboard or the equivalent, each sheet being endless or cylindrical. At the inner and outer surfaces of the sheets, they are joined by paper sheets 11, impervious to air, the outer one of which is preferably stiffer as shown and extended or continued downwardly below the same as at 12.

Said portion 12 is extended inwardly and upwardly forming a wall 13.

The wall structure for the bottom of the container is substantially similar to that of the side wall although flat, such bottom being suggested generally at 14. Such bottom includes any desired number of disks of corrugated pasteboard at 15, with sheets of paper 16 on opposite sides thereof and with a thicker sheet of paper 17 at the top, having a depending marginal flange 18 overlapped by the wall 13, the latter being depressed or beaded into the same as at 19.

All of the parts mentioned of the cylindrical wall or body 10 and the bottom closure 14, are secured together in any suitable manner usually by means of an adhesive.

The top of the container is in the form of a removable closure generally designated 20. This closure is not adhered or permanently connected to the container 10 in any manner. It has any desired number of corrugated paper sheets or

disks 21 on both sides of which are sheets of paper 22, impervious to air. Between the innermost sheets 22, is a stiffer sheet or disk of paper 23, having an upwardly extending annular wall 24. An outer annular wall 25, removably slides over the upper end of the container 10, with the lowermost sheet 22 engaging the ends of the various walls thereof, closing the air spaces of the corrugations. Said wall 25 is turned inwardly at 26, over the upper end of the wall or flange 24, having a marginal flange 27, engaging the upper wall 22 and the flange or wall 26 preferably being beaded as at 28 into the flange 24. Obviously, all of the parts of the removable closure 20 are connected together in any suitable manner as by means of an adhesive.

Closure 20 may be readily removed in order to place a bottle, foods or the like, within the interior of the container 10 and then replaced and the parts may be carried against danger of leakage, formation of frost on the exterior, or the same becoming too hot, and without any other disadvantages.

Various changes may be resorted to provided they fall within the spirit and scope of the invention.

I claim as my invention:

1. An insulated container of the class described having an outer cylindrical wall provided with an interior annular returned portion at one end, an end wall disposed inwardly of said end having a marginal flange disposed between said returned portion and cylindrical wall, corrugated walls disposed in the space between said end wall and end of the cylindrical wall, and means also in said space to support the corrugated walls and seal the space containing them, and hollow wall means within the cylindrical wall having end contact with said end wall.

2. An insulated container having a cylindrical wall, corrugated walls interiorly thereof providing air spaces, a closure having an outer cylindrical wall slidably applicable over the first mentioned cylindrical wall, said second mentioned cylindrical wall having an inner returned portion at the top thereof, a top wall within the second mentioned cylindrical wall having an upwardly extending marginal flange disposed between said returned portion and second mentioned cylindrical wall, means below the top wall to extend over the corrugated walls to close the air spaces thereof, a sealing member across the closure in abutment with the lower edge of said returned portion, and corrugated wall means between said top wall and said sealing member.

EDGAR ALVIN WICKSTROM.
